UNITED STATES PATENT OFFICE.

EDWARD M. BENTLEY, OF NEW YORK, N. Y.

SWITCH FOR ELECTRIC RAILWAYS.

SPECIFICATION forming part of Letters Patent No. 508,672, dated November 14, 1893.

Application filed August 31, 1889. Serial No. 322,622. (No model.)

To all whom it may concern:

Be it known that I, EDWARD M. BENTLEY, a citizen of the United States, residing at New York, in the county of New York and State of New York, have invented certain new and useful Improvements in Switches for Electric Railways, of which the following is a specification.

My invention relates to electric railways and its object is to provide a switch of simple and reliable construction which will control the movement of a traveling contact device at a turn-out, and which is arranged, preferably, to guide the contact device normally along the main line when the car is traveling in one direction, but which will yield to permit the passage of the contact device when a car comes out of the siding in the opposite direction.

With these objects in view I have provided a switching section of conductor which forms at one end a continuation of the branch conductor, and which at its other end normally bears against the main line wire.

My invention is illustrated in the accompanying drawings wherein—

Figure 1 represents a plan view of the main, branch and switching conductors. Fig. 2 is a side view of the same. Fig. 3 is a cross-section of the conductor showing a grooved contact device in engagement with its under side. Fig. 4 is a similar view illustrating in modified form the contact device, and Fig. 5 is a plan view showing a modified form of the switching conductor.

In the views "A" is the main supply conductor which is herein shown as extending continuously beyond the switch.

"B" is the siding, or turn-out conductor which terminates at the hood "C," and "D" is the switching conductor, forming a continuation of "B" and normally spring-pressed against the main conductor. This last function may be secured either by making the switching conductor itself of a spring plate, as shown in Figs. 1 and 2, one end of which is riveted, or bolted, to the hood "C" or by pivoting the conductor, as at "D'" Fig. 5 and providing a spring "E" attached to the conductor at one end through the crank-arm

"d'," and at its other end to a fixed support "d'." To enable the contact device to clear the main conductor when taking the switch, the free end of the tongue is so shaped as to sink below or otherwise gradually depart from 55 the level of the main conductor. This is shown in Fig. 2.

In the drawings I have shown the conductors suspended above the roadway by means of the hood "C" which has three downwardly 60 projecting arms "a, a', a'" to which the line conductors are attached, while the hood itself is supported by a hanger "F," which includes the insulator "G." It is, however, apparent that the present invention can be applied 65 with equal advantage to any system of line conductors, wherever located, and I do not, therefore, intend to be limited to an overhead system alone.

"H" Fig. 2 represents conventionally a contact device consisting of a supporting rod, and a grooved wheel "I" at its outer end adapted to form a traveling engagement with the under side of the supply conductor; this form of contact device may be connected to a 70 vehicle in any well known, or suitable manner.

In Fig. 4 the contact device is shown as consisting of an upright rod pivoted to the car on a longitudinal axis, and making contact with the side of the conductor, a spring 80 connection "J" being provided to maintain the contact device constantly against the conductor with a yielding pressure.

I claim as my invention—

1. The combination with the main and 85 branch working conductors A, B, of an electric railway, of the switching conductor D, one end of which forms a direct continuation of the branch conductor B, and is movable laterally around its end as a center toward 90 and away from the main conductor, and a spring normally holding the free end of the switching conductor against the main conductor.

2. The combination with the main and 95 branch conductors, of a switching conductor normally spring pressed against the main conductor, a trolley pole carrying at its upper end a grooved contact device running in engagement with the under side of the conduct- 100

tors, and means for automatically depressing said contact below the normal plane of the main conductor at the junction, whereby said contact is enabled to pass from the main to 5 the branch line without jar.

3. The combination with a suspended continuous main conductor and a branch conductor, of a trolley pole carrying at its upper end a grooved contact device engaging with 10 the under side of the conductor, and a switching section of conductor, having a free end normally in contact with the main conductor

and having its lower edge so shaped that it sinks gradually below the level of the under side of the main conductor, whereby it guides 15 the contact laterally across and clear of said main conductor when taking the switch.

This specification signed and witnessed this 21st day of August, 1889.

EDWARD M. BENTLEY.
